UNITED STATES PATENT OFFICE.

MORRIS W. ASKIN, OF WASHINGTON, DISTRICT OF COLUMBIA.

MUSICAL INSTRUMENT.

Application filed August 23, 1921. Serial No. 494,679.

This invention relates to a musical toy and more particularly to a novel and improved structure which can be operated by a descending object, consecutively striking the musical sound bars.

A further object of the invention is to provide a musical instrument of compact arrangement and simple construction.

With these objects in view and others which will be manifest and suggested as the purpose and nature of my invention are revealed in the following specification, taken in connection with the accompanying drawing, which illustrates a preferred embodiment of the invention,

Fig. 1 is a vertical cross-section of the musical toy.

Fig. 2 is a horizontal cross-section taken on line 2—2 of Fig. 1.

Fig. 3 is a horizontal cross-section taken on line 3—3 of Fig. 1.

Fig. 4 is a vertical cross-section taken on line 4—4 of Fig. 1.

Fig. 5 is an enlarged detail showing means of attaching the sound bars.

Fig. 6 is a modified form showing the musical instrument used as a toy.

Fig. 7 is an end section of Fig. 6 showing the trigger mechanism to release the balls.

Referring now to the drawing wherein similar reference characters designate corresponding parts throughout the several views, 1 designates the sound box, 1^a is the opening through which the sound escapes, 1^b is the opening through which the balls may be removed.

The upper stair-like support 2, running diagonally with the sound box for the keys, is fastened at 3 at the upper end, and supported on tube 4, at its lower end.

The lower stair-like structure, 2^a, is arranged diagonally with the sounding box in inverse direction with the upper, and is fastened at its upper end to the side plate of the sounding box, and at its lower end to the bottom of the box.

The upper end of the tube 5, conforms in section with an opening 5^b in the upper cover of the sounding box. The tubes 4 and 5 are fastened to the stair-like structures 2^a and 2 by clamps 6.

The sound producing sound bars of the instrument, 7, are attached to the stair-like structures 2 and 2^a by screws 9, and inserted between the sound bars and structures 2 and 2^a, are felt washers 8.

The modification primarily intended as a toy as shown in Fig. 6, comprises a stair-like structure 16, supported in an inclined plane by any suitable means such as the inclined legs, 16^a. 10 designates a U shaped tube, opened at its lower end. The upper end of the tube forms a magazine 11.

The trigger mechanism 12 regulates the descent of the balls, 5^a. It is pivoted on the stair-like structure by pin 12^a. It consists of a fork 12^b and 12^c, the part 12^b being the forward one and serving to support the forward end of the foremost ball. The part 12^c of the fork serves to support the series of balls when the foremost ball is released. Two openings 12^d, in the magazine are provided to allow an oscillating movement of the two parts of the fork. A tray 17 is provided to catch the balls as they emerge.

A toy, known as "Chicken Little", marked 13, straddles the tube 10, and on its descent, its roller 14 pivoted at 15, strikes the sound bars and produces the tones. It is understood that this modified form can be used either with the "Chicken Little" or with the descending balls 5^a operated by the trigger mechanism.

Having shown and described my invention, what I now claim as new and desire to secure by Letters Patent of the United States is:

1. In a device of the class described in combination, a sound box, stair-like structures, supported therein, a guide on said structures, sound producing bars attached to the steps of the structure and means moving down said steps and guided by said guide to strike sound producing keys.

2. In a device of the class described, in combination, a sound box, stair-like structures supported therein, a guide supported on said structures, sound producing bars attached to the steps of the structure and balls moving down said steps and guided by said guide to strike sound producing keys.

3. In a device of the class described in combination, a sound box, a stair-like structure supported therein, a guide supported on said structure, sounding bars attached to said structure and means moving along said stairs to strike said bars.

4. In a device of the class described, in combination, a stair-like structure, sound bars attached to said steps, a guide supported in spaced relation to steps, means moving along said steps for striking said sound bars,

one end of said guide serving to hold said means, and a release mechanism, cooperating with said structure and guide, to control the descent of said sounding means.

5. In a device of the class described, in combination, a sound box, a stair like structure supported in said box, sound producing means attached to the steps of said structure, a guide supported in spaced relation to said steps, sound bar actuating means moving along said steps and a guide to direct said

sound bar actuating means, an opening at the top of the box through which said sound bar actuating means may be dropped a space in the lower end of said box serving to collect 15 said sound bar actuating means after their descent and an opening in said box, through which said sound bar actuating means may be removed.

In testimony whereof I affix my signature.

MORRIS W. ASKIN.
